BY

HIS ATTORNEY

UNITED STATES PATENT OFFICE.

GEORGE A. WEBER, OF NEW YORK, N. Y.

RAIL-JOINT.

SPECIFICATION forming part of Letters Patent No. 605,265, dated June 7, 1898.

Application filed November 5, 1897. Serial No. 657,586. (No model.)

To all whom it may concern:

Be it known that I, GEORGE A. WEBER, of the city, county, and State of New York, have invented a certain new and useful Improvement 5 in Rail-Joints, of which the following is a specification.

This invention embraces means for joining the contiguous ends of two adjacent rails comprised in a car-track and which are of 10 different sizes or weights, as it is technically expressed.

I will describe a rail-joint wherein are embodied the features of my invention, and then express the novelty in the claims.

15 In the accompanying drawings, Figure 1 is a side elevation of a finished joint. Fig. 2 is a plan of Fig. 1. Fig. 3 is a horizontal longitudinal section through the joint. Fig. 4 is a side elevation of a fish-plate embodied in 20 the invention. Fig. 5 is a vertical cross-section through a rail and parts embodied in the invention adjacent to the end of the rail.

Similar letters of reference designate corresponding parts in all figures.

25 A A' represent the adjacent ends of two rails differing in size or weight and forming a portion of a car-track.

Rails differing in weight vary generally in height, and it is the purpose of the present 30 invention to afford a means for joining the ends of such rails which shall give a secure joint and which will also bring the upper surfaces of the said rails in line with each other.

The end sections of the rails A A' rest upon 35 a rail-chair B, having a horizontal bearing-plate b and an upwardly-extending bolt-holding flange b'. The chair will preferably be supplied with an outwardly-extending lip b''. The bearing-plate b is stepped, or, in 40 other words, it is provided with two bearing-surfaces in different planes, the vertical distance between which is equal to the difference in height of the two rails A A'. Thus when the rails are in place their upper running-surfaces 45 will be true or in line with each other.

The means for securing the rail ends to the chair and to each other comprise side or fish plates C C'. These fish-plates are made so that when the inner flanges of two contiguous 50 rails are in alinement differences in relative positions of the webs, the feet, and heads or

flanges will be compensated for by differences in depth and thickness of the fish-plate. The fish-plates may be made to bear snugly against the faces of the webs of two contiguous rails, 55 or they may be hollowed, so as to bear only at the top and bottom. By these means a secure joint is made between rails of differing weights and one which insures the inner face of the heads of such rails being kept in perfect alinement.

The fish-plate C, adjacent to the bolt-supporting flange b' of the rail-chair, is channeled or recessed longitudinally on its outer surface, as shown at c, into which fits a packing 65 or washer strip C², shaped to fit the recess in fish-plate C. This strip is clamped against the flange b' and the several parts firmly secured together by means of bolts C³.

Having described my invention, what I 70 consider as new, and desire to secure by Letters Patent, is—

1. In combination with a support for two rail ends having two integral portions forming bearing-surfaces in different planes, of 75 fish-plates for securing the ends of the rails together and adapted to compensate for differences in position of the remaining parts when the inner faces of the heads of said rails are in alinement, substantially as specified. 80

2. The combination of a rail-chair having a bolt-holding flange and a stepped bearing or rail-supporting surface upon which the ends of the rails rest, fish-plates and fastening-bolts, said fish-plates being adapted to 85 compensate for differences in position of the rails when in position on the chair, substantially as specified.

3. The combination with a support for two rail ends having integral portions forming 90 bearing-surfaces in different planes and with a bolt-holding flange at one edge thereof, fish-plates for securing the ends of the rails together and adapted to compensate for differences of position of the rail ends when the 95 inner faces of the heads of said rails are in alinement, one of said fish-plates being adapted to have its edges bear against the bolt-holding flange, substantially as specified.

4. The combination of a rail-chair having 100 a bolt-holding flange and a stepped bearing or rail-supporting surface, upon which the

ends of the rails rest, fish-plates adapted to compensate for differences in position of the rails when in position on the chair, a packing or washer strip interposed between the bolt - holding flange and the adjacent fish-plate, and fastening-bolts, substantially as described.

In testimony whereof I have signed my name to this specification in the presence of two subscribing witnesses.

GEORGE A. WEBER.
